(**) Term: **14 Years**

(57) **CLAIM**

The ornamental design for a mesh back rest for a chair, as
shown and described.

DESCRIPTION

(21) Appl. No.: **29/434,807**

(22) Filed: **Oct. 17, 2012**

(30) **Foreign Application Priority Data**

Jul. 31, 2012 (CN) 2012 3 0354224

FIG. 1 is a perspective view of a mesh back rest for a chair
according to a first embodiment of my new design;
FIG. 2 is a front view of the mesh back rest shown in FIG. 1;
FIG. 3 is a rear view of the mesh back rest shown in FIG. 1;
FIG. 4 is a top side view of the mesh back rest shown in FIG.
1;

(51) LOC (9) Cl. **06-01**

FIG. 5 is a bottom side view of the mesh back rest shown in
FIG. 1;

(52) U.S. Cl.

FIG. 6 is a right view of the mesh back rest shown in FIG. 1;
FIG. 7 is a left view of the mesh back rest shown in FIG. 1;

(58) **Field of Classification Search**

FIG. 8 is a perspective view of a mesh back rest for a chair
according to a second embodiment of my new design;
FIG. 9 is a front view of the mesh back rest shown in FIG. 8;
FIG. 10 is a rear view of the mesh back rest shown in FIG. 8;

USPC D6/334-336, 364, 365, 366, 369,
D6/374, 379, 380, 716, 716.1, 716.2, 716.3,
D6/716.4; 297/284.4, 284.7, 452.13, 452.29,
297/452.3, 452.46, 452.56, 452.64

FIG. 11 is a top side view of the mesh back rest shown in FIG.
8;

See application file for complete search history.

FIG. 12 is a bottom side view of the mesh back rest shown in
FIG. 8;
